Inventor:

Halle M. Corrine Young.

UNITED STATES PATENT OFFICE

112,473

DESIGN FOR A STREET TRAFFIC SIGNAL

Hallie M. Corrine Young, Oklahoma City, Okla.

Application October 7, 1938, Serial No. 80,310

Term of patent 7 years

To all whom it may concern:

Be it known that Hallie M. Corrine Young, a citizen of United States, residing at Oklahoma City, in the county of Oklahoma and State of Oklahoma, have invented a new, original, and ornamental Design for a Street Traffic Signal, of which the following is a specification, reference being had to the accompanying drawing, forming a part thereof.

Fig. 1 is a front perspective view shown partly

broken for convenience of illustration of a street traffic signal showing my new design.

Fig. 2 is a sectional view taken on line 2—2 of Fig. 1; and

Fig. 3 is a sectional view taken on line 3—3 of Fig. 1.

I claim:

The ornamental design for a street traffic signal, as shown and described.

HALLIE M. CORRINE YOUNG.
